UNITED STATES PATENT OFFICE

VICTOR KOENIGSHOFER, OF UNION CITY, NEW JERSEY, ASSIGNOR TO ALUMINUM COMPANY OF AMERICA, OF PITTSBURGH, PENNSYLVANIA, A CORPORATION OF PENNSYLVANIA

COLLAPSIBLE TUBE CAPPING MACHINE

Application filed January 24, 1930. Serial No. 423,018.

This invention relates to machines for applying caps to thin walled containers, and more particularly, to machines for capping collapsible tubes.

5 Among the objects of the invention is to provide a machine that will apply a cap to a collapsible tube automatically.

Another object of the invention is to provide, in a collapsible tube capping machine, mechanism by which the rotational movement required for screwing a cap upon the threaded neck of a tube may be caused to automatically cease upon the occurrence of any jamming action or at the termination of 15 the capping operation, as for example, when a cap is screwed home.

Another object of the invention is to provide a collapsible tube-capping machine which may be readily adapted to the purpose of applying caps of different sizes to tubes of different lengths.

Other objects involving novel constructions and combinations of parts will appear in the specification and in the claims thereof 25 setting forth a preferred embodiment of my invention which may be fully understood from the detailed description and drawings, in which:—

Fig. 1 is an elevation of one side of the capping machine.

Fig. 2 is an elevation of the rear of the capping machine.

Fig. 3 is an enlarged front view of the upper portion of the capping machine.

Fig. 4 is an enlarged detail view on line 4—4 of Fig. 1.

Fig. 5 is a sectional view on line 5—5 of Fig. 4.

Fig. 6 is a sectional view on line 6—6 of Fig. 4.

Fig. 7 is a sectional view on line 7—7 of Fig. 8.

Fig. 8 is a sectional view on line 8—8 of Fig. 7.

Fig. 9 is a sectional view on line 9—9 of Fig. 7 with parts broken away.

Fig. 10 is a detail fragmentary showing of the slip connection between a mandrel and driving means therefor.

Fig. 11 illustrates, in plan and with parts

broken away, the approach of a cap to a collapsible tube.

For disclosing my invention I have illustrated a machine having a turret carrying several mandrels upon which collapsible tubes may be mounted. The mandrels and tubes are brought to a cap-applying station, and there rotated. As a mandrel rotates at the cap-applying station, a cap-carrying device places a cap against the threaded neck 55 of the tube and holds it there until the cap and the tube are assembled. The cap-carrying device is then moved to a position where it picks up another cap which is to be placed upon the next tube to be presented at the 60 cap-applying station.

For convenience in describing the invention, the locus of travel of the cap-applying or cap-carrying device may be defined as extending between two stations; a cap-receiving station from which a cap is picked up by the cap-applying device, and a cap-applying station where the cap is applied or affixed to the neck of a collapsible tube.

Referring to the drawings and particularly to Figs. 1, 2 and 3, the mandrels, 10, are freely rotatable on pins, 11, carried by turret, 12, which is mounted on a shaft, 13. Shaft 13 is journaled in bearings, 14, 15, in the upper fixed frame, 16. Frame 16 is 75 mounted upon the base of lower frame, 17, which, for the purpose of clarity or illustration, is shown in dot-and-dash lines. Power for driving turret shaft, 13, is derived from a motor, 18, and is transmitted 80 through gearing 19, 20 to the driving element, 21, of a Geneva lock. The Geneva driving element, 21, carries a single driving pin, 22, and has a locking surface, 23, which 85 successively engages co-operating locking surfaces, 24, between successive engagements of pin, 22, with slots, 25, of the driven element, 26, of the Geneva lock. Since the driven element, 26, is keyed to shaft 13, 90 turret, 12, which is also fastened to shaft, 13, is driven intermittently each time pin, 22, engages a slot, 25. One slot, 25, is provided for each mandrel, 10, and the speed ratio of the gearing is such as to position the mandrels 95 successively at a cap-applying station suffi- 100

ciently long to permit a cap to be screwed upon the threaded neck of a tube. A friction band, 27, Fig. 1, is operative upon a disk carried by shaft, 13, so as to take-up any slack likely to exist and to insure justification of the position of each mandrel at the cap-applying station.

In order to enable an operator to control the movement of shaft, 13, and the operation of the machine, a square jawed clutch, 28, is keyed to shaft 29 and is slideable axially thereon. The square jawed clutch, 28, is movable into and out of engagement with a co-operating clutch element, 31, carried by gear, 32, which forms part of gearing, 20, and which is loosely mounted on shaft, 29. Clutch collar, 28, may be moved in and out of engaging relation with clutch element, 31, by means of a treadle, 33. This motion is transmitted through link, 34, to lever, 35, which is pivoted at 36. Clutch element, 28, is illustrated in Fig. 1 as being out of engagement with clutch element, 31, and in this position gearing, 19, will operate idly and no movement will be transmitted to gearing, 20.

Having reference to Fig. 1, a roller, 38, is attached to, or may form part of each mandrel, 10, and when a mandrel is opposite the cap-applying station it will be rotated by means of a friction disk, 39, which contacts roller, 38. Friction disk, 39, is driven from a shaft, 40, between which and the friction disk there is a slip connection which is adapted to discontinue the driving relation between shaft 40 and friction disk 39. This slip connection, which is illustrated in detail in Fig. 10 and will be described herein-after, is for the purpose of discontinuing the drive of mandrel, 10, under certain conditions. Shaft 40 carries a pinion 41 which meshes with gear 42 mounted so as to turn with shaft 43. Shaft 43 is driven continuously through a sprocket chain drive 44 which is driven from shaft 45. Shaft 45 carries the driving element 21 of the Geneva lock which rotates continuously while the machine is in operation.

The upper frame 16 carries a sliding-block guide rail upon which is mounted a cross-head or sliding-block, 47, Figs. 1, 3, 7, 8 and 9. Sliding-block 47, which is in the form of a housing, has a dovetail connection, 48, with the guide rail 46 and the sliding-block may be slid along the rail by means of a stationary screw 49 which engages nut 50 extending from the sliding-block. The screw 49 may be rotated by hand wheel 51 and when the sliding-block 47 has been placed in a desired position along the guide rail 46 the wing-headed screw 52 may be tightened so as to hold the block in a fixed position in relation to the rail.

Adjustability of the position of sliding-block 47, along screw, 49, is provided so as to enable the machine to be adjusted for the

purpose of adapting it to place caps upon collapsible tubes of different length and whose necks extend different distances from the mandrel-supporting turret, 12. Block 47 carries the cap-applying device and its set 70 position determines the locus of travel of the cap-applying device as it is moved between forward and rearward limits as seen in Fig. 1.

Sliding-block 47 also carries a super-structure 75 upon which is mounted the journal bearing 54 for a shaft 55. Shaft 55 has affixed thereto a hopper 56 in which caps are placed. The rotation of hopper, 56, causes the caps to be delivered to the upper end of a chute, 57, Fig. 3, with the open end of the cap facing away from the hopper. Any well known type of hopper may be used for feeding caps to the chute. Shaft 55 is driven by means of a belt, 58, which engages a pulley, 85 59, attached to shaft, 43, Fig. 1.

Shaft 43 is journaled in bearings 60, 61, which are carried by sliding-block 47, and a collar, 62, which is pinned to shaft, 43, causes the shaft to move with the sliding-block when adjustment of the position of the sliding-block is being made. The rear end of shaft, 43, is slideable in bearing, 63, on frame, 16, and a spline, 64, is provided so as to maintain keyed engagement with gear, 42, and sprocket-wheel, 65, for any axial position of sliding-block, 47, and shaft, 43, in respect to frame 16. Gear 42 and sprocket-wheel, 65, are restrained from lateral movement by bearing, 63, and bearing bracket, 100 63a. Sliding-block, 47, is in the form of a housing whose ends provide journal bearings for rock-shafts, 68, 69, Figs. 7 and 8. These rock-shafts form a part of the cap-applying device and they have affixed to their forward ends arms, 70, 71, respectively.

During a cap-applying operation rock-shafts, 68, 69, rock towards each other as a cap is clasped by the jaws at the lower ends of these arms and they are rocked away from each other after a cap has been applied to the threaded neck of a tube. In order to move the arms, 70, 71, from a cap-receiving position to a cap-applying position, rock-shafts 68, 69, are slidably mounted in their journal bearings so as to permit axial movement of the shaft relatively to the sliding-block 47.

For accomplishing the axial movement of shafts 68, 69, I provide a cam, 73 fixed to shaft 43 and a follower 74, which carries a roller, 75, engaging the surface of cam, 73. Follower 74 bridges shafts 68, 69 and carries them with it as the follower is moved when cam 73 rotates. The fixed relation of follower 74 and of shafts 68, 69, is maintained by collars 76, 77, 78 and 79. A spring, 80, having one end secured to follower 74, and its other end anchored at 81 to the rear wall 120 of the sliding-block, 47, causes the cam roller 125 130

75 to be maintained against the surface of cam 73.

For the purpose of controlling the rocking movements of shaft, 68, a cam, 83, is provided. This cam is keyed to shaft, 43, and during its rotation it rocks an arm, 84, which carries a roller 85, bearing upon the surface of cam, 83. Arm 84 is pinned to shaft 68 and as cam 83 is rotated shaft 68 is rocked.

10 Likewise, for the purpose of controlling the rocking movements of shaft 69, a cam 88 is provided. This cam is keyed to shaft 43, and during its rotation it rocks an arm, 86, which carries a roller, 87 bearing upon the

15 surface of the cam, 88. Arm 86 is pinned to shaft 69 and as cam 88 is rotated, shaft 69 is rocked. Spring 112 at the lower ends of arms 70, 71 maintains the rollers of arms 84, 86 against their respective cams.

20 Since rock-shafts, 68, 69 are movable in an axial direction in relation to shaft 43, I have provided splines 89, 90 on opposite sides of shaft 43 for permitting axial movements of cams, 83, 88, in accordance with the axial movement of rock-shafts 68, 69.

25 Cams 83, 88 are joined together by a member, 91, having a groove, 92, which is engaged on one side by a finger, 93, depending from the boss of the arm, 84, which is mounted on the shaft, 68, and is engaged on the opposite side by a finger, 94, depending from the boss of arm 86 which is mounted on shaft 69.

30 Since fingers 93 and 94 are pinned to shafts 68, 69 respectively, they operate to cause member 91 and cams 83, 88, to be moved axially on shaft 43 when rock-shafts 68, 69 are moved axially under the influence of cam 73.

35 Chute 57, Fig. 3, delivers caps to the vertical chute, 96, which is formed by front and rear strips 97, 98, and side strips 99, 100, Figs. 1, 3, 4, 5 and 6.

40 The cross-sectional dimensions of the chute may be varied for the purpose of accommodating caps of different sizes. Winged nuts 101, are provided so that the spacing of side strips, 99, 100 may be changed with ease, and the depth of the chute, 96, may be varied by using spacing elements, 102, of different thicknesses to suit caps of different heights. Chute 96, is carried by super structure, 53, as illustrated in Fig. 1.

45 The caps, 104, are vertically aligned in chute, 96, with the skirt of each cap in contact with the inner edges of the side strips, 99, 100. The lower cap of the string of caps in the chute rests upon a spring, 106, which is mounted on strip, 97. The lower end of strip, 97, carries a block or table, 107, adjustable in height and upon which a cap is deposited, and from which the cap is removed by the cap-applying device. The table, 107, may be identified as the cap-receiving station and its position is such as to support a cap so that its axis is in

line with the axis of a tube at the cap-applying station.

The two arms, 70, 71, of the cap-applying device carry at their lower ends jaw plates, 108, 109 which are affixed to the arms 70, 71, 70 by means of pin and slot connections, 110, 111. These jaw plates have curved clasping surfaces for engaging the skirt of a cap. The two arms, 70, 71, are biased toward each other by means of a spring, 112, which extends between their lower ends and which causes rollers 85, 87 to continually bear upon cams 83, 88 respectively.

50 As the cap-engaging device is brought by the action of cam, 73, to the cap-receiving station, a pair of pins, 113, 114, which are carried by arms, 70, 71, respectively, are brought into contact with bail, 115. Bail, 115, is mounted so as to rock about rock-shaft, 116, which carries the two bell crank levers 117, 118, upon which bail, 115, is mounted. Bell crank levers, 117, 118, also carry a bail, 119, which is on the other side of chute 96. Bail, 119, has mounted thereon a rod, 120, whose lower end has a cap-engaging element, 121. 90 The upper end of rod, 120, is biased rearwardly and downwardly by a spring, 122, whose fixed end is anchored to a pin, 123, extending laterally from a bracket, 124. Rod, 120 is limited in its downward movement in 95 respect to bail, 119, by collar, 126, and a spring, 127 is provided for normally maintaining collar, 126, in contact with bail, 119.

55 As rock-shaft, 116, is rocked clock-wise, Fig. 5, rod, 120, is caused to descend and the 100 course of its lower end, 121, will be determined partly by the position of cam surface, 130, which is adjustable. As rod, 120, descends, lip 121 engages the inner surface of the skirt of the cap reposing upon spring, 106, 105 and forces the cap downwardly below spring, 106, to a position of rest upon table, 107.

60 The action of rod, 120, causes the spring, 106, to be temporarily deflected a sufficient degree to permit the lowermost cap to descend 110 to table, 107, but it will immediately restore itself beneath the cap immediately above the one removed.

65 As illustrated in Fig. 5, the arms, 70, 71, are rearward of the chute, 96, and if the arms 115 are moved forwardly toward a position for engaging a cap on table, 107, pins, 113, 114, carried by the arms, engage bail, 115, and cause the rod, 120, to descend and place a cap upon table, 107, where it may be picked up 120 by the cap-engaging jaws when arms, 70, 71, are permitted to approach each other under the action of spring, 112. Spring 132, having one end connected with bail, 119, will restore bail, 119, rod, 120, and bail, 115, to the positions illustrated in Fig. 5 when pins 113, 114, are withdrawn from contacting relation with bail, 115. After the cap-engaging device is moved from the cap-receiving station, pins 125 113, 114, no longer contact with bail 115. 130

As referred to hereinabove, a slip connection is provided between the friction roller 39, and shaft 40, so as to permit discontinuance of the rotary motion of a mandrel, 10, after a cap has been screwed home upon the threaded neck of a tube. As may be readily seen in Fig. 10, the slip connection between shaft 40, and roller 39, consists of a slip clutch which may be easily adjusted for permitting slip to take place in accordance with the sensitivity desired.

Shaft, 40, has pinned thereto a pair of collars, 139, 140, between which is mounted a member, 141, which is free to rotate relative to shaft, 40, when slippage is occurring.

Member, 141, carries roller, 39, which is held in place by means of a pair of nuts, 142, 143, mounted upon the threaded hub of member, 141. Shaft 40, has an enlarged portion, 144, enclosed within chamber 145, of member, 141. A collar, 146, is loosely mounted upon shaft, 40, and is fixed in relation to member, 141, by means of set screws, 147, 148. A pair of springs, 149, 150, joined in series relation, are coiled about hub, 144, one end of spring, 149, being anchored in collar, 146, and one end of spring, 150, being anchored in member, 141. The arrangement is such that when shaft, 40, rotates, member, 141, and roller, 39, are carried therewith because of the frictional relation existing between springs 149, 150, and hub, 144.

As illustrated in Fig. 10, when shaft, 40, rotates downward, the tendency of the springs is to rotate with the shaft and thereby cause member, 141, to be rotated. It is apparent that should friction roller, 39, be held from rotation, the holding of the ends of springs, 149, 150, and the continuance of rotation of shaft, 40, would tend to relieve all gripping action of the springs on hub, 144.

It will be appreciated that a gripping tendency of the springs may be varied by changing the initial tension of the springs and provision for accomplishing this is provided by the collar, 146, which may be adjusted in either direction about shaft, 40, before the set screws, 147, 148, are tightened. The adjustment of the clutch is such that it will release and discontinue the drive of a mandrel as soon as a cap has been screwed onto a tube far enough to offer a certain desired resistance.

The cap-engaging jaws of the plates, 108, 109, are arranged so as to engage the skirt of a cap and are provided with grooves, 152, 153, Fig. 11, so as to accommodate the flange, 154, of a cap. These grooves are provided to assure the proper closing of the cap engaging jaws upon a cap and are not intended to engage the peripheral edge of the flange, 154. Accordingly, caps having either polygonal or round bordered flanges may be accommodated in this machine. The cap-engaging surfaces, 155, 156, engage the skirt of the

cap and the pressure applied to the cap by means of spring, 112, is such as to hold the cap during a cap-applying operation. The jaws are designed so as not to mar the cap and to permit slippage of the cap should the slip connection to the mandrel fail to function.

It will be appreciated that the tubes fit sufficiently tight on the mandrels so that the drive of a tube is accomplished through the frictional relation between the tube and mandrel. There is a possibility of a tube slipping on the mandrel or of slippage between roller 39 and disk 38 should the friction slip connection fail to function at any time.

It is apparent that the tube could be rotated by causing roller, 39, to directly contact the exterior surface of the tube, but since such an arrangement might possibly cause the wrinkling or twisting of thin walled tubes, I prefer to cause rotation of a tube by having roller, 39, engage the mandrel.

Operation

An operator places tubes on mandrels, 10, as turret, 12, is rotated step by step in a clockwise direction, Fig. 3. Each movement of the turret brings a tube-carrying mandrel to the cap-applying station.

As soon as a mandrel carrying a tube is brought to a cap-applying station, friction roller, 39, which rotates continuously, contacts roller, 38, and causes the mandrel, and the tube carried thereon, to rotate. While the tube is rotating, cam, 73, is permitting the cap-applying device, under the action of spring, 80, to approach the end of the collapsible tube. The arms, 70, 71, of the cap-applying device carry a cap and place the same against the threaded neck of the tube and the rotation of the mandrel at the cap-applying station causes the tube to engage the cap. After the cap and tube are engaged, cams, 83, 88, operate to rock arms, 70, 71, so as to release the cap. Subsequent to the release of the cap, cam 73 causes the rock-shafts, 68, 69, to move to the left, Fig. 1, toward the cap-receiving station.

During their travel to the left, pins, 113, 114, carried by arms, 70, 71, respectively, come into contact with bail, 115, and cause bail, 119, Fig. 5, to be rotated so as to cause rod, 120, to displace a cap from its position on spring, 106. The released cap is deposited upon table, 107, at the cap-receiving station. When arms, 70, 71, have reached their limit of travel toward the cap-receiving station they are permitted to approach each other to pick up the cap on table, 107. This action is permitted by cams, 83, 88, and results from the influence of spring 112. During this operation turret, 12, has rotated another step and will have carried a second mandrel and tube to the cap-applying position. When cam, 73, has rotated sufficiently, spring 80 will operate in conjunction with

cam, 73, to cause the cap-carrying arms to move to the right and cause the cap carried thereby to engage the threaded neck of a tube.

As the tubes are capped they may be removed from their mandrels by an operator.

The invention is capable of wide variation and relationship of parts without departure from the nature and principle thereof. I do not restrict myself unessentially in the foregoing or other particulars, but contemplate such alterations and modifications within the scope of the appended claims as may be found advisable.

What is claimed is:

15. 1. In a collapsible tube capping machine, the combination comprising means for holding a tube at a cap applying station, means for supporting a cap, and a capping device, said capping device comprising a pair of 20 axially movable rock-shafts, arms carried by said rock-shafts, cap engaging jaws carried by said arms, means for rocking said rock-shafts to cause the jaws to engage a cap on said support, and means for moving said jaws 25 so as to present the cap carried thereby to the threaded neck of a collapsible tube.
2. In a collapsible tube capping machine, the combination comprising means for holding a tube at a cap applying station, a cap receiving apparatus at a cap receiving station opposite said cap applying station and axially aligned with the axis of the tube held at said cap applying station, a cap applying device movable between said two stations, said cap applying device comprising pivoted arms carrying cap-engaging jaws, means for closing said jaws upon a cap at the cap receiving station, and means for causing said device to carry the cap to the cap applying station.
40. 3. In a collapsible tube capping machine, the combination comprising means for holding a tube at a cap applying station, a cap receiving apparatus at a cap receiving station opposite said cap applying station and axially aligned with the axis of the tube held at said cap applying station, a cap applying device movable between said two stations, said cap applying device comprising spring pressed jaws for engaging a cap, cam means controlling the closing of said jaws upon a cap at the cap receiving station, and means for moving said capping device toward the aligned tube, said last named means comprising a spring and cam and follower means.
55. 4. In a collapsible tube capping machine, the combination comprising means for holding a tube at a capping station, a capping device, said capping device comprising a pair of axially movable rock-shafts, arms carried by said rock-shafts, cap engaging jaws on said arms, means for rocking said rock-shafts to engage a cap, and means for moving said rock-shafts axially to carry a cap to a capping station where the cap can engage the neck of a collapsible tube.

5. In a collapsible tube capping machine, the combination comprising cap engaging means, means for moving said cap engaging means to and from a cap receiving station and a cap applying station, means for positively operating said cap engaging means to release a cap after engagement of the cap with the neck of a collapsible tube, and resilient means for causing said cap engaging means to engage and hold a cap, said resilient means being subject to the control of said last named means and permitted thereby to engage a cap at the cap receiving station.

6. In a collapsible tube capping machine, the combination comprising a pair of pivoted arms, cap engaging means carried by said arms, means for moving said arms to and from a cap receiving station and a cap applying station, means for positively rocking said arms away from each other after engagement of the cap with the neck of a tube, and resilient means for causing said cap engaging means to engage and hold a cap, said resilient means being subject to the control of the pivoted arms by said last named means and permitted thereby to engage a cap at the cap receiving station.

7. In a collapsible tube capping machine, the combination comprising means adapted to carry a cap from a cap receiving station to a cap applying station to apply the cap to the neck of a collapsible tube, means for moving said cap carrying means between said stations, and means enabling a variation in the locus of travel of said first named means.

8. In a collapsible tube capping machine, the combination comprising means for holding a tube at a cap applying station, a cap receiving apparatus at a cap receiving station, said apparatus comprising means for supporting a cap, means for carrying a cap between said stations, means for actuating said cap carrying means, and means enabling variation of the position of said cap receiving station and cap carrying and actuating means in respect to the cap applying station.

9. In a collapsible tube capping machine, the combination comprising means for holding a tube at a cap applying station, a cap receiving apparatus at a cap receiving station, said apparatus comprising means for supporting a cap, means for carrying a cap between said stations, means for actuating said cap carrying means, and means whereby the spaced relation of said cap receiving station and said cap applying station may be varied so as to enable tubes of different lengths to be capped.

10. In a collapsible tube capping machine, the combination comprising means for holding a tube at a cap applying station, cap applying means, means for controlling the actuation of said cap applying means, a cap receiving apparatus comprising means for supporting a cap, and a cross-head settable in

70

75

different positions in respect to said cap applying station, said cross-head carrying said cap applying means, controlling means and cap receiving apparatus.

5. 11. In a collapsible tube capping machine, the combination comprising means for holding a tube at a cap applying station, a cap receiving apparatus at a cap receiving station, said apparatus comprising a cap support, a hopper and a chute for guiding caps from said hopper to the cap receiving apparatus means for carrying a cap from said cap receiving apparatus to said cap applying station, and means enabling a change in the position of said cap receiving apparatus, hopper, chute and cap carrying means in respect to the cap applying station.

20. 12. In a collapsible tube capping machine, the combination comprising means for holding a tube at a cap applying station, a cap receiving apparatus at a cap receiving station, said apparatus comprising a cap support, rock-shafts carrying arms having cap engaging jaws for carrying a cap from the cap receiving station to the cap applying station, means for axially moving and for rocking said rock-shafts, and a cross-head, movable relatively to said cap applying station, said cross-head having means for moving said last named means and rock-shafts with the cross-head.

25. 13. In a collapsible tube capping machine, the combination comprising a chute for guiding caps from a hopper, means retaining a cap in said chute, a cap receiving apparatus at a cap receiving station, said apparatus comprising a cap support, tube holding means at a cap applying station, means movable between said stations for removing a cap from said support and for applying the cap to the tube, and means actuated by said last named means for causing the cap retaining means to release a cap and deposit the same at the cap receiving station where it may be picked up by the said last named means.

30. 14. In a collapsible tube capping machine, the combination comprising means for holding a tube at a cap applying station, a cap receiving apparatus at a cap receiving station, said apparatus comprising a support for a cap and cap applying means adapted to carry a cap from the support to the cap applying station, said cap applying means comprising replaceable plates having jaws shaped to grip the skirt of a cap.

35. 15. In a collapsible tube capping machine, the combination comprising means for holding a tube at a cap applying station, a cap receiving apparatus at a cap receiving station, said apparatus being axially aligned with the tube, said cap receiving apparatus comprising means for supporting a cap with its axis aligned with the axis of the tube, said supporting means being adjustable to align caps of different sizes with the axis of the tube,

and means for transferring a cap from said supporting means to the cap applying station.

16. In a collapsible tube capping machine, the combination comprising cap engaging means, means for moving said cap engaging means from a cap receiving station to a cap applying station, supporting means for a tube at the cap applying station, said supporting means comprising a rotatable mandrel engaging the inner surface of the tube, a roller on said mandrel, and rotary means adapted to contact said roller to rotate said mandrel and tube.

70. 17. In a collapsible tube capping machine, the combination comprising a turret carrying rotatable mandrel for mounting collapsible tubes, means for rotating said turret so as to present a tube bearing mandrel at a cap applying station periodically, means for transferring a cap from a cap receiving station to a tube at the cap applying station and into engagement with the neck of a tube, means for rotating the mandrel, power means for actuating said last named means, and a slip connection between said power means and said last named rotating means enabling a discontinuance of the rotation of said mandrel, said slip connection having means whereby the maximum torque transmitted thereby may be adjusted.

75. 18. In a collapsible tube capping machine, the combination comprising a mandrel for supporting a collapsible tube, means for carrying said mandrel to a station where a cap may be applied to a tube mounted on the mandrel, a cap-carrying device movable axially of a tube mounted on a mandrel at the cap-applying station, said cap-carrying device including a pair of spring pressed arms engaging a cap, and means for causing relative rotary motion between the tube and cap as the tube and cap are engaged.

80. 19. In a collapsible tube capping machine, the combination comprising a turret, a plurality of mandrels on said turret, means for rotating said turret for presenting the mandrels at a cap applying station, a chute, cap supporting means for receiving a cap from said chute, means whereby the positions of the chute and the cap supporting means may be varied at will in respect to the turret, a cap carrying device movable between the cap supporting means and the cap applying station, and means operated by said cap carrying device for causing a cap to be deposited on the cap supporting means.

85. 20. In a collapsible tube capping machine, the combination comprising tube holding means, a fixed supporting frame therefor, a guide rail extending from said frame, a sliding block mounted on said guide rail, a hopper and chute carried by said sliding block, and means enabling adjustment of the posi-

tion of said sliding block along said guide rail.

21. In a collapsible tube capping machine, the combination comprising tube holding means, a fixed supporting frame therefor, a guide rail extending from said frame, a sliding block mounted on said guide rail, a hopper and chute carried by said sliding block and a cap carrying device movable between said chute and tube holding means, said cap carrying device being mounted upon said sliding block.

22. In a collapsible tube capping machine, the combination comprising tube holding means, a fixed supporting frame therefor, a guide rail extending from said frame, a sliding block mounted on said guide rail, a hopper and chute carried by said sliding block, a cap carrying device mounted upon said sliding block, means carried by said fixed supporting frame for moving said cap-carrying device between said chute and tube holding means, and means for positioning the sliding block along said guide rail.

23. In a collapsible tube capping machine, the combination comprising a table for supporting a cap, a chute, a resilient member supporting caps in said chute, an element for removing a cap from said resilient member to deposit the same on said cap supporting table, said element having a lip for engaging the interior of a cap, and means for yieldingly guiding said element to cause the lip to engage the interior of a cap or to pass over a cap having no interior to be engaged.

24. In a collapsible tube capping machine, the combination comprising means for supporting a cap, and means for delivering caps to said cap supporting means one at a time, said delivering means including an element engaging within the interior of the cap and therefore capable of delivering to the cap supporting means only caps which have their recessed sides facing in the same direction.

25. In a collapsible tube capping machine, the combination comprising a chute, means maintaining a cap within said chute, a table for supporting a cap, and means engaging within the interior of the cap for transferring a cap from said chute to said table only if the cap faces in a given direction.

In testimony whereof I hereto affix my signature.

VICTOR KOENIGSHOFER.
